UNITED STATES PATENT OFFICE.

ALEXANDER MARTHINIUS GJESTVANG, OF CHRISTIANIA, NORWAY.

FURNITURE-SPRING.

SPECIFICATION forming part of Letters Patent No. 402,434, dated April 30, 1889.

Application filed February 23, 1888. Serial No. 265,077. (No model.) Patented in Norway January 3, 1888, No. 773; in Sweden January 31, 1888, No. 1,399; in England May 11, 1888, No. 7,052, and in France June 4, 1888, No. 190,995.

To all whom it may concern:

Be it known that I, ALEXANDER MARTHINIUS GJESTVANG, a citizen of Norway, residing at Christiania, Norway, have invented certain new and useful Improvements in Furniture-Springs, (for which I have obtained Letters Patent in the following countries, to wit: Norway, January 3, 1888, No. 773; Sweden, January 31, 1888, No. 1,399; England, May 11, 1888, No. 7,052, and France June 4, 1888, No. 190,995;) and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The invention relates to that class of springs more especially adapted for use in chairs and upholstered furniture; and it consists in structural features and in the combination, with the spring, of retaining devices to secure such spring in position for use.

The object of my invention is to provide a strong yet elastic or yielding spring for chairs and the like, and a simple and efficient means for securing the springs in position for use.

Referring to the drawings, Figures 1, 2, and 3 are detail views of different forms of spring-arms detached or separated from the spring shown in Fig. 5. Fig. 4 is an isometric view of the two halves of the fastening device, and Fig. 5 is a plan view showing the spring connected with its support or retaining devices.

The spring consists, essentially, of a plurality of radially-arranged spring-arms formed of a single wire, and in Fig. 1 I have shown one of the arms in its simplest form, the wire 40 A being doubled and bent into or substantially into a half-ellipse, the upper bent portion, a , constituting the spring-bearing, while the diverging branches a' serve to secure the spring to the retaining devices.

According to the degree of elasticity the spring is to have, and also to some extent according to the degree of resistance it is to offer to pressure exerted thereon, I form in each branch of the wire portion A of which 50 the arms are formed, at the smaller end of

the half-ellipse, one or more convolutions, a^2 , as shown in Fig. 2. The elasticity of the spring may be increased by forming additional convolutions a^3 in the diverging branches of the wire A, as shown in Fig. 3. In practice I preferably form a plurality of convolutions at the points named for the purposes stated. 55

The spring when applied to a chair is arranged with its arms in radial planes, so that their free ends or bearings will converge toward a common center. This may be done in a very simple and effective manner by means of the retaining plates or disks B and C, (shown in Fig. 4,) for instance. The plate C is provided with projections c , bounded by 60 two radial lines, said projections decreasing in width from the periphery toward the axis of the disk or plate. The plate B, on the contrary, is provided with recesses b , into which said projections fit. 70

The branches a' of each arm-section of the spring are laid on opposite sides of the projections c on the plate or disk C, and the plate or disk B is placed thereon so that its recesses b will register with the projections c 75 on disk C, and the whole may then be firmly secured together by a single axial bolt, D.

Of course the system of spring described may be applied to upholstered furniture in general, as well as to spring-mattresses, and 80 for the latter purpose the free end a of the spring arms or sections may be moved to come close together at a point in the vertical plane of the axis of the retaining-bolt and above the latter. 85

It will be observed that with a construction of spring such as described a strong durable spring may be produced very cheaply, and that any desired degree of elasticity may be given to such a spring. 90

Having described my invention, what I claim, and desire to secure by Letters Patent, is—

1. A spring consisting of a plurality of spring-arms bent into or substantially into 95 the form of a half-ellipse and arranged to converge toward a common center, said spring being constructed of a single continuous wire, substantially as described.

2. A spring consisting of a plurality of

spring-arms converging toward a common center, each spring-arm comprising two members or branches bent into or substantially into the form of a half-ellipse, and having 5 one or more convolutions formed in the members thereof at a point or points intermediate of the extremes of such branches, substantially as and for the purposes specified.

3. A spring consisting of a plurality of 10 spring-arms converging toward a common center, each spring-arm comprising two members or branches bent into or substantially into the form of a half-ellipse, and having one or more convolutions formed in the members thereof at a point or points intermediate of the extremes of such arms, said spring 15 being made of a single or continuous wire,

substantially as and for the purposes specified.

4. A spring consisting of a plurality of 20 spring-arms, each comprising two members or branches bent into the form of a half-ellipse, in combination with the retaining-disk B, provided with the angular recesses b, and the retaining-disk C, provided with corresponding angular projections, c, substantially as and for the purposes specified. 25

In testimony whereof I affix my signature in presence of two witnesses.

ALEXANDER MARTINIUS GJESTVANG.
